FIG. 1 is a perspective view taken from the front left of a handrail unit embodying my new design;

FIG. 2 is a top view of the unit shown in FIG. 1;

FIG. 3 is a front view of the unit shown in FIG. 1;

FIG. 4 is a left end view of the unit shown in FIG. 1;

FIG. 5 is a section taken as indicated by the lines and arrows 5—5 in FIG. 3;

FIG. 6 is a back view of the unit shown in FIG. 1;

FIG. 7 is a bottom view of the unit shown in FIG. 1;

FIG. 8 is a front view of an alternate embodiment of a handrail unit embodying my new design;

FIG. 9 is a left side view of the unit shown in FIG. 8; and

FIG. 10 is a section taken as indicated by the lines and arrows 10—10 in FIG. 8.

The mounting surfaces shown in broken lines form no part of the design and are shown to illustrate environment only.

The handrail portion of the unit has been foreshortened for the sake of clarity and convenience in illustration.

The top, bottom and perspective views of the alternate embodiment have not been shown since these could easily be reproduced from the embodiment shown in FIGS. 1 through 7.

I claim:

The ornamental design for a handrail unit, as shown and described.
